UNITED STATES PATENT OFFICE

JOHN MEYER, OF COVINGTON, KENTUCKY.

BEER-COOLER.

SPECIFICATION forming part of Letters Patent No. 323,712, dated August 4, 1885.

Application filed June 8, 1885. (No model.)

To all whom it may concern:

Be it known that I, JOHN MEYER, a citizen of the United States, and a resident of Covington, in the county of Kenton and State of Kentucky, have invented certain new and useful Improvements in Beer-Coolers, of which the following is a specification.

My invention relates to apparatus for cooling beer preparatory to storing it. Its object is to lessen the consumption of ice and reduce the beer to a lower temperature than is now accomplished by the process in common use. These objects are accomplished by the means illustrated in the accompanying drawings, in which—

Figure 1 is a view partially in central vertical section and partially in elevation of my improved apparatus. The section is taken through line *y y* of Fig. 2, which figure is a vertical section of the ice-crushing rolls and the chamber within which they are contained. This section is taken at right angles to the view shown in Fig. 1, and through the line *x x* of said figure.

Similar reference-letters indicate like parts wherever they occur throughout the views.

A represents the box or case of the ice-crusher, in the ends of which are journaled rollers *B*. These rollers have teeth or points *b* projecting from their peripheries, those upon the one roller being arranged to pass those upon the other in alternate rows. The shafts *b'* of the roller are provided at one end on the outside of the case *A* with gear-wheels *b''*, the teeth of which mesh, thus causing both wheels to revolve in opposite directions when power is applied by a belt passing over the pulley *b''*, secured upon the opposite end of one of the shafts. The case *A* has a hopper, *a*, above the crushing-rollers, into which the ice which is fed to the rollers is placed, and below the rollers is a similar hopper, *a'*, which conveys the crushed ice passing from the rollers to a tank, *C*, which is arranged below the case *A* and between the case and the cistern *D*. Upon the right-hand side of Fig. 1 is shown, in elevation, a coil of cooling-pipes, *E*. This device is of ordinary construction, and will require no detail description here. As ordinarily used, water is forced from a cistern, as *D*, the

water being cooled in the cistern by placing blocks of ice in it, up through the pipe *H* and thence through the coil of the cooler, and discharged through the upper pipe, *e*, of the cooler. The beer in the meantime enters the trough *d* on top of the cooler, which trough is perforated or slotted on its lower edge to allow the beer to drip over the pipes into the trough *e'*, located below the cooler, from which trough it passes through a pipe, *G*, to the storing-tank. Instead of carrying this pipe *G* to the storing-tank, I carry it through the tank *C*, near its top, and connect it with a coil, *G'*, the lower coil of which is connected to the discharge-pipe *g*, which leads to the storing-tank. A pipe, *e*, leads from the tank *C* into a cistern, *D*.

The operation of the device is as follows: The blocks of ice are placed in the hopper *a*, the rollers *B* set in motion, the crushed ice passing through and into the tank *C*, which should ordinarily be kept well filled with the crushed ice. As this ice melts by the beer passing through it the water drips down through pipe *e* into cistern *D*, from which it is drawn by the pump and forced through the cooler *E*. The beer, dripping over the cooler into the trough *e'*, is partially cooled. From the trough it passes through pipe *G* and through coil *G'*, and is discharged through the pipe *g* at a much lower temperature than it is possible to reduce it even when it passes over a number of coolers, *E*. If desired, a quantity of salt may be fed with the ice to produce even a lower temperature. By this means I am enabled to save a considerable quantity of ice and require less than half the cooling-surface ordinarily employed for this purpose.

What I claim is—

1. The combination of the ice-tank *C*, a coil arranged within said tank, and the ice-crusher arranged to discharge crushed ice into said tank, with the cooler *E*, and pipes *G g*, the said pipes being connected to the opposite ends of the coil, substantially as and for the purpose specified.

2. The ice-tank *C*, arranged above the cistern *D*, and having a discharge-pipe leading from the bottom of the tank into the cistern, *g*.

the case A a', and the ice crushing rolls B, arranged above the tank and within the case A to discharge the crushed ice into the tank, in combination with cooler E, pipes H, and 5 pump for forcing water from the cistern through the cooler, with the pipe G, coil G', and pipe g to carry the beer from the trough

of the cooler through said pipes and coil to the storing-tank, substantially as hereinbefore set forth.

JOHN MEYER.
